SLIPPAGE PERMITTING CLAMP

Robert L. McCoy, Baltimore, Md., assignor to
 Locke Insulator Corporation, Baltimore, Md.,
 a corporation of Maryland

Application August 12, 1931, Serial No. 556,649

2 Claims. (Cl. 248—31)

The invention relates to clamps particularly designed for supporting the conductors of high tension transmission lines.

It is well known that it is customary to support transmission line conductors by means of strings of insulators suspended from towers located considerable distances apart. It frequently occurs through breakage of the conductor or as the result of an accumulation of ice or sleet on one or more spans of the conductor that an unusual and excessive lateral strain comes upon one or more towers. To relieve this strain it has been suggested to employ supporting clamps having cam or other means to open them up or release their holding power upon the conductor so that it may slip through and effect equalization of the strain at opposite sides of any tower so that detriment thereto by reason of the excess lateral strain which would otherwise occur will be avoided. However, in the use of such so-called releasing clamps there are certain objections. To begin with the conductor is not of solid construction but comprises a core about which are wrapped or wound rods or wires usually of smaller gauge than the core and formed customarily of aluminum. When the usual type of releasing clamp opens up there is a certain point at which the conductor will start to slip and it frequently occurs that the break causes the exterior wires or rods to move relatively to the core, resulting in what is commonly called "bird caging". Furthermore in the use of the ordinary type of releasing clamp it is difficult to predetermine the exact holding power so that it may be known definitely at what degree of strain the clamp will open.

It is with the above facts in view that I have devised the present invention which has for its general object the provision of a conductor suspension clamp of such construction that its holding power is positively limited so that the cable may slip, without the clamp opening, when a certain predetermined number of pounds of pressure or strain is exerted upon the conductor.

An important object of the invention is to provide a clamp of this character which may be formed of what are commonly considered standard parts with the simple addition of means cooperating with the clamping bolts for limiting the closing together of the relatively movable parts so that the holding power may be adjusted.

An additional object is to provide a slippage permitting clamp which always remains closed and which is therefore free from complicated mechanism such as cams, springs and the like

which constitute necessary parts of a releasing clamp of the opening type.

Yet another object is to provide a clamp of this character which will be very simple and inexpensive to make and assemble, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is a side elevation of a clamp constructed in accordance with my invention, and

Figure 2 is a view half in end elevation and half in section on the line 2—2 of Figure 1.

Referring more particularly to the drawing I have shown the clamp as comprising a main lower or body member 10 formed with a curved seat 11 which extends longitudinally for the reception of the conductor, not shown, the ends of the member 10 being flared or belled as indicated at 12 and the ends of the seat being correspondingly flared or longitudinally curved as at 13 for the purpose of avoiding bringing any bending strains on the conductor in the event of vibration thereof or what is known as "dancing". At opposite sides the body member 10 is formed with laterally extending trunnions 14 with depending lips 15, the trunnions being received within circular holes 16 in links 17 adapted to be bolted at 18 on to the lower end of a string of suspension insulators, not shown, in the customary manner. The depending lip 15 prevents accidental disengagement of the links from the trunnions but as an additional safeguard cotters 19 may be provided passing through the trunnions outwardly of the links. Furthermore the body member 10 is formed at opposite sides with pairs of laterally extending ears 20.

Cooperating with and located above the body member 10 is the movable clamping member 21 which is formed with a transversely curved seat 22 adapted to contact with the conductor, this seat being moreover preferably slightly longitudinally bowed as indicated by the dotted line in Figure 1. Projecting from opposite sides of the member 21 are ears 23 apertured for the passage of clamping bolts 24 which pass through holes 25 in the ears 20 and which are equipped with spring washers 26 and nuts 27. While the washers could be omitted they provide a certain re-

silence in the connection between the members 10 and 21 and are therefore advantageous.

The principal feature in the present invention is the provision of means for limiting the holding power of the clamp and this is effected by means cooperating with the bolts 24. To carry out this feature the ears 20 are preferably formed with counterbores or recesses 28 extending downwardly from their top sides and of course concentric with the holes 25. Within these recesses are located bushings 29 of any suitable metal and which have outstanding flanges 30 overlying the tops of the ears 20 and engaged by the undersides of the ears 23.

15 When the clamp is assembled upon the conductor in an obvious manner and when the bolts 24 are inserted and the nuts 27 applied thereto and turned up tightly it is apparent that the flanges 30 located between the ears 20 and 23 will limit the degree of clamping action exerted by the members 10 and 21 upon the conductor. It will be noted that the seats 11 and 22 are rather gradually curved, the curvature being of much greater radius than the radius of a conventional conductor. By virtue of this arrangement it is clear that the clamp may be used for supporting conductors of different diameters. When a larger conductor is to be used or when it is desired to limit still further the pressure exerted by the 30 clamping members the idea is to use bushings 29 having flanges 30 of greater thickness. In this way a clamp of one pattern such as that shown may be used in a large number of places and under widely varying circumstances by the simple 35 expedient of having on hand a number of interchangeable bushings 29 with flanges 30 of different thicknesses. There is no necessity for the bushings to be secured within the recesses 28 provided for their reception as they could not 40 under any circumstances get out of place.

From the foregoing description and a study of the drawing it will be apparent that I have thus provided a very simple clamp adaptable to widely different circumstances as regards the size of the conductor to be supported and the degree of pressure to be exerted thereon. The clamp is easily 45 assembled and applied and is of course used in ex-

actly the same manner as any other of this type though it will be clear that when the strain on the conductor at either side of a tower from which the conductor is supported by means of this special clamp exceeds a certain predetermined 5 degree the conductor may slip so that the unequal strains at both sides may be equalized, thus avoiding bringing excessive strains upon the tower such as might cause damage thereto. It is thought from the above that the construction, 10 operation and advantages will be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. A clamp comprising relatively movable 25 clamping members adapted to receive and retain a conductor between them and provided with suspension means, bolts passing through said members for securing them together in clamping engagement upon the conductor, and bushings 30 surrounding said bolts and having flanges located between the clamping members for limiting the holding power of the bolts.

2. A conductor supporting clamp comprising 35 a pair of clamping members disposable upon opposite sides of a conductor and equipped with suspension means, said members having laterally extending ears, bolts passing through the corresponding ears for holding the clamping members in clamping engagement upon the conductor, 40 certain of said ears being formed with recesses, and bushings located within said recesses and through which the bolts pass, said bushings having flanges located between the confronting ears 45 for limiting the clamping pressure exerted by said members upon the conductor.

ROBERT L. McCOY.
